IRWIN HUEBNER, OF ALLENTEWON, PENNSYLVANIA.

AUTOMOBILE RADIATOR VENTILATOR.

Application filed January 11, 1928. Serial No. 246,069.

This invention relates to ventilators useful in connection with the radiators of automobiles, more particularly to a type capable of attachment at the filler openings of the 5 radiators.

The main object of my invention is to provide for effective circulation of air through the upper headers of automobile radiators above the surface of the liquid 10 cooling medium therein to the end of counteracting vapor pressure and preventing excessive evaporation through boiling, especially when highly volatile liquids, such as alcohol or the different compounded solutions now available on the market, are employed as cooling agents for cold weather driving.

My invention is further concerned with provisions to automatically control circulation of cooling air through the radiator in accordance with temperature conditions therein; as well as with provisions whereby the ventilators may be rendered inoperative when desired.

How the foregoing as well as still other objects and attendant advantages may be readily realized in practice will be manifest from the detailed description which follows of the typical embodiment of this invention 30 delineated in the drawings.

Fig. I is a fragmentary sectional view through the upper header of an automobile radiator showing my improved ventilator in place.

Fig. II is a front view of the ventilator without the radiator cap and the thermostatically-governed valve controlling circulation of air through the device.

Figs. III and IV are cross sectional views taken as indicated respectively by the arrows III—III and IV—IV in Fig. II.

Fig. V is a perspective view of the shut-off valve means whereby the device may be rendered inoperative at will.

Fig. VI is a fragmentary view of the stem of the ventilator with a detachable air filtering collar which may be employed with the device when automatic air flow control is not desired.

Fig. VII is a perspective view of the air filtering collar just referred to.

Fig. VIII is a fragmentary view showing an alternative form of automatic air flow control; and,

Fig. IX is a perspective view of a sleeve

valve embodied in the organization of Fig. VIII.

With reference first more in detail to Figs. I to IV of these illustrations, it will be observed that the ventilator of my invention embodies a flat hollow circular head 10 wherefrom depends a tubular shank or stem 11, which, in the present instance, is integrally formed with said head. As shown in Fig. I, the stem 11 extends down into the upper header 13 of the automobile radiator through a central aperture in the screw cap 14 over the neck 15 about the filling opening. The screw cap 14 is secured to the ventilator by a clamp nut 16 which opposes a circumferential stop flange 17 of the stem 11 and engages the screw threaded portion 11^a of the latter. The ventilator is subdivided interiorly by a central vertical partition 18 through the medial plane of the head 10 with provision, in said head, of horizontal axially-aligned circular anterior and posterior air influx and efflux openings 19, 20, and through the stem 11, respectively communicating vertical inflow and outflow ducts 21, 22 which terminate at the lower end of the stem 11 within the radiator header 13, in laterally directed openings 21^a, 22^a. To facilitate angular flow of the air between the influx and efflux openings 19, 20 and

the communicating vertical ducts 21, 22, I employ, crosswise of said openings, deflector vanes 25, 26, which, as shown in Fig. I, are arcuate in cross section with their inner edges extending into closer proximity to the partition 18, as considered upward from the lowermost one of each group. As a consequence of this arrangement, the air flow is proportionately and uniformly distributed incidental to passage into and out of the vertical flow ducts 21, 22. The vanes 25, 26, are supported at opposite ends by perimetric members 27, 28, in the present instance in the form of flange rings having a friction fit within counter recessions 29, 30 of the 80 head 10.

In order that the device may be rendered inoperative at will, I may equip either or both the removable vane supporting inserts with a shut off valve such as shown in Figs. I, II and V, having the form of a split band 31 with bearing at the inside of the ring flange 27. At the bottom, the valve band 31 has a cut out 32 for normal registry

90 as a port over the upper entrant end of the 95 head 10.

100 In order that the device may be rendered inoperative at will, I may equip either or both the removable vane supporting inserts with a shut off valve such as shown in Figs. I, II and V, having the form of a split band 31 with bearing at the inside of the ring flange 27. At the bottom, the valve band 31 has a cut out 32 for normal registry

105 as a port over the upper entrant end of the 110 head 10.

duct 21. A lateral projection or tongue 33 of the valve band 31 extends through an arcuate motion limiting slot 34 in the flange ring 27 and serves as a manipulating handle, 5 see Figs. II and III more particularly.

The port 32 may be protected by wire mesh screening as conventionally indicated in Figs. I, III and V to preclude entry of dust into the radiator with the air.

10 For the purpose of automatically controlling the flow of air through the radiator in accordance with temperature conditions within it, I provide, as shown in Fig. I, a sleeve valve 35 around the lower end of the 15 stem 11. This sleeve valve has ports 36, 37 for registry with the lateral openings 21^a, 22^a of the vertical air flow ducts 21, 22, and is secured to the upper end of a conventional bellows thermostat 38. At the bottom, the 20 thermostat 38 is attached to a plate 39 which is immovably supported by screws 40 taking into a fixed collar 41 on the stem 11.

The operation of the device is as follows: Incidental to travel of the automobile, air 25 is forced into the anterior influx opening 19 of the head 10, and directed, by concerted action of the deflecting vanes 25, downward into the vertical inflow duct 21 for discharge through the lateral outlet 21^a and induction into the frontal portion of the radiator header 13 as indicated by the arrows 30 in Fig. I. An air pressure is thus set up within the radiator head with resultant displacement concurrently of a corresponding 35 amount of air therefrom, escape being by way of the lateral opening 22^a into the vertical outflow duct 22, and thence into the posterior efflux opening 20 of the head 10 where the deflecting vanes 26 redirect the 40 air for horizontal rearward discharge from the ventilator. In this way, it will be seen that air is constantly circulated through the upper header of the radiator over the surface of the liquid medium therein to assist 45 in maintaining it cool, thereby counteracting and carrying off vapor pressure and at the same time preventing excessive evaporation. Operation as just described is of course subject to control by the sleeve valve 50 35 under governance by the thermostatic bellows 38, in accordance with the temperature within the radiator. In other words, in practice, as the temperature within the radiator rises and the bellows 38 expands, 55 the sleeve valve 35 is gradually moved upward from the full closed position when the motor is cold (as at starting), to full open or illustrated position in contact with the collar 41; with attendant variation in the air 60 flow.

Figs. VIII and IX show an alternative form of automatic flow control in which the thermostatic bellows 38^x is attached to the lower end of the stem 11, and enclosed 65 by the sleeve valve 35^x which it carries.

Thus as the bellows 38^x expands, the sleeve valve 35^x is moved downward (instead of upward as in Fig. I) to bring its ports 36^x, 37^x into registry with the lateral openings 21^a, 22^a of the vertical flow ducts 21, 22.

In instances when the thermostatic control is not desired, I may employ, instead of the filtering screen on the shut-off valve 31, a collar such as shown at 42 in Figs. VI and VII to fit the lower end of the stem 11 and 75 having perforations 43 distributed over areas corresponding to the openings 21^a, 22^a into the vertical ducts 21, 22. The screen collar 42 is detachably held in place through cooperation of bayonet-lock notches 44 in 80 its upper edge with studs 45 projecting laterally from the stem 11.

From the foregoing it will be seen that I have provided a very simple and efficient means for setting up circulation of air within the upper header of the radiator with attainment of the various advantages hereinbefore pointed out. I do not wish to be limited to the precise details of construction herein shown since my invention is 90 capable of considerable modification; for example, the ventilator may be constructed integral with the radiator cap 14, and the head 10 made otherwise than circular. Also, the stem 11 may, either in whole or in 95 part, be made separate from the head 10 if found convenient from the standpoint of economical manufacture.

Having thus described my invention, I 100 claim:

1. An automobile radiator ventilator of the character described having horizontally-aligned anterior and posterior influx and efflux openings and respectively communicating vertical inflow and outflow ducts into 105 the radiator; and deflecting vanes to divert the air angularly for easement of its passage into and out of said vertical ducts.

2. An automobile radiator ventilator of the character described having horizontally-aligned anterior and posterior influx and efflux openings and respectively communicating vertical inflow and outflow ducts into 110 the radiator; and deflecting vanes transversely of the influx and efflux openings to angularly divert the air for easement of its passage into and out of said vertical ducts.

3. An automobile radiator ventilator of the character described comprising a flat hollow head and a depending tubular stem extending down into the radiator, the whole subdivided by a vertical partition through the medial plane of the head with provision in said head, of horizontally-aligned anterior and posterior influx and efflux openings, and respectively communicating vertical inflow and outflow ducts through the stem opening laterally into said radiator.

4. An automobile radiator ventilator of the character described comprising a flat 120

hollow head, and a depending tubular stem extending down into the radiator, the whole subdivided by a vertical partition through the medial plane of the head with provision 5 in said head, of horizontally-aligned anterior and posterior air influx and efflux openings and communicating vertical inflow and outflow ducts through the stem; and deflecting vanes extending transversely of the influx and efflux openings to angularly divert the air for easement of its passage into and out of said vertical ducts.

5. An automobile radiator ventilator of the character described comprising a flat hollow head and a depending tubular stem extending into the radiator, the whole subdivided by a vertical partition through the medial plane of the head with provision in 10 said head, of horizontally-aligned anterior and posterior air influx and efflux openings, and communicating vertical inflow and outflow ducts through the stem; and deflecting vanes extending transversely of the influx and efflux openings to angularly divert the 15 air for easement of its passage into and out of the vertical ducts, the inner edges of the vanes extending into closer proximity to the vertical partition, as considered upwards from the lowermost one of each group, for 20 proportionate distribution of the air flow.

6. An automobile radiator ventilator of the character described having horizontally-aligned anterior and posterior influx and efflux openings and respectively communicating vertical inflow and outflow ducts into the radiator; and removable inserts having 25 perimetric flanges to fit within the influx and efflux openings of the head, and transversely extending deflecting vanes to angularly divert the air for easement of its passage into and out of said vertical ducts.

7. An automobile radiator ventilator of the character described having horizontally-aligned anterior and posterior influx and efflux openings, and respectively communicating vertical inflow and outflow ducts into the radiator; deflecting vanes to divert the air angularly for easement of its passage 40 into and out of said vertical ducts; and 45 means responsive to temperature variations within the radiator to control air flow through the ventilator.

8. An automobile radiator ventilator of the character described comprising a flat hollow head and a depending tubular stem extending down into the radiator, the whole subdivided by a vertical partition through the medial plane of the head with provision 50 in said head of horizontally-aligned anterior and posterior influx and efflux openings and 55 respectively communicating vertical inflow and outflow ducts through the stem opening laterally into said radiator; a sleeve valve 60 slideable on the stem; and means responsive to temperature variations within 65

the radiator to shift the sleeve valve in governing air flow through the lateral openings of said vertical ducts.

9. An automobile radiator ventilator of the character described having horizontally-aligned anterior and posterior influx and efflux openings and respectively communicating vertical inflow and outflow ducts into the radiator; and removable inserts having perimetric flanges to fit within the influx 75 and efflux openings of the head, transversely-extending deflecting vanes to angularly divert the air for easement of its passage into and out of the vertical ducts; and shut-off 80 valve means carried by one of the inserts aforesaid movable over the top of one of said ducts.

10. An automobile radiator ventilator of the character described having horizontally-aligned circular anterior and posterior air 85 influx and efflux openings and respectively communicating vertical inflow and outflow ducts into the radiator; removable inserts with circular flanges to fit the influx and efflux openings, and transversely-extending 90 vanes to angularly divert the air for easement of its passage into and out of the vertical ducts; and a shut-off valve band capable of being rotatably shifted within the circular flange of one of the inserts and having 95 a port for registry with the upper end of one of said vertical ducts.

11. An automobile radiator ventilator of the character described having horizontally-aligned circular anterior and posterior air 100 influx and efflux openings and respectively communicating vertical inflow and outflow ducts into the radiator; and removable inserts with circular flanges to fit the influx and efflux openings and transversely-extending 105 vanes to angularly divert the air for easement of its passage into and out of the vertical ducts; a shut-off valve band capable of being rotatably shifted within the circular flange of one of the inserts, said band having a port with screening thereover for 110 registry with the upper end of one of said vertical ducts.

12. An automobile radiator ventilator of the character described comprising a flat hollow head and a depending tubular stem extending down into the radiator, the whole subdivided by a vertical partition through the medial plane of the head with provision 115 in said head, of horizontally-aligned anterior and posterior influx and efflux openings, and respectively communicating vertical inflow and outflow ducts through the stem opening laterally into said radiator; and movable screen means adapted to filter the air passing 120 through the ventilator vertical ducts.

In testimony whereof, I have hereunto signed my name at Allentown, Pennsylvania, this 5th day of January, 1928.

IRWIN HUEBNER.
